Des. 217,469
Patented May 5, 1970

217,469

DECORATIVE LIGHT BULB HOLDER

Donald W. Lo Giudice, Youngstown, Ohio, assignor to Garcia Products, Inc., Youngstown, Ohio, a corporation of Ohio

Filed May 15, 1969, Ser. No. 17,626

Term of patent 14 years

Int. Cl. D11—05

U.S. Cl. D29—1

FIG. 1 is a front plan view of the decorative light bulb holder.

FIG. 2 is a side view thereof. The back is substantially plain.

I claim:

The ornamental design for a decorative light bulb holder, as shown and described.
